UNITED STATES PATENT OFFICE.

FRANCIS G. SUSEMHL, OF DETROIT, MICHIGAN, AND LUTHER K. JEWETT, OF BOSTON, MASSACHUSETTS.

CAR-TRUCK.

SPECIFICATION forming part of Letters Patent No. 361,846, dated April 26, 1887.

Application filed August 4, 1886. Serial No. 209,962. (No model.)

To all whom it may concern:

Be it known that we, FRANCIS G. SUSEMHL, of Detroit, county of Wayne, and State of Michigan, and LUTHER K. JEWETT, of Boston, county of Suffolk, and State of Massachusetts, have invented an Improvement in Car-Trucks, of which the following description, in connection with the accompanying drawings, is a specification, like letters on the drawings representing like parts.

Our invention, herein to be described, has for its object to improve that class of car-trucks called "swing-motion" trucks, or a truck wherein the bolster which supports the weight of the car-body is supported upon springs, in turn supported in such manner by links as to permit the bolster to move longitudinally, or to swing with its load at right angles to the truck and track.

Heretofore the bolster of swinging trucks has contained large wooden beams, and the springs on which the bolster rests have been sustained upon a swing-plank extended across the truck, and this swing-plank has been supported by links sustaining a bar supported by metallic transoms, made preferably as two channel-bars, having between them an open space for the reception of the bolster, as well represented in the journal called "National Car Builder," page 93 of the edition for July, 1885, the journal being published at New York, N. Y. I am also aware that in some swing-trucks the links which support the swing-plank and springs have been located at a considerable distance inside the arch-bars toward the center of the truck, or just over the track or rails, and in case the links referred to are broken the swing-plank drops directly upon the track, and the bolster is left entirely without support, such breaking of the links usually resulting in derailing the car-truck.

To obviate this great objection to the employment of so-called "swing-motion" trucks, we have provided the car-truck with a metallic U-shaped transom, to take the place of the said channel-bars, and have rigidly attached the said transom to arch-bar-supporting blocks, and have suspended the links to support the springs, the bolster, and car-body directly from

rocking bars sustained above and parallel to 50 the said arch-bars, the links supporting the springs and transom embracing the arch-bars, rather than a bar sustained by the transoms, the said springs and links falling in the line occupied by the arch-bars and truss and outside the track, and in case the links for any reason are broken the devices supporting the springs and bolster are caught in the transom and the car-truck will run as before, only the bolster will not swing as before. 60

The particular features in which our invention consists will be pointed out in the claims.

Figure 1 is a top or plan view of a truck containing this invention. Fig. 2 is a section of Fig. 1 in the dotted line *xx*. Fig. 3 is a longitudinal section of Fig. 1 in the line *x'*, and Fig. 4 a perspective view of the arch-bar-sustaining block or casting removed.

The wheels *a*, axles *a'*, and the housings *a''* and their contained boxes are and may be of any usual construction.

The transom *b*, as well as the bolster *b'*, is herein shown as composed of strong sheet-metal shells, preferably steel, of about one-fourth of an inch thick, the same being bent 75 into substantially U shape, to form a box or trough with rounded corners, as at *b'*, the said transom and bolster being each in one piece, instead of in separate pieces riveted together, as in United States Patent No. 279,951, the 80 bolster being narrower than the transom, so as to be free to rise and fall therein. The bolster is sustained by springs *b''*, (herein shown as four,) the said springs being so located at the ends of the transom and bolster as to be effective in reducing concussion in the line of the arch-bars or trusses to be described. The transom and bolster are both strengthened internally by angle-iron, as *b'''*.

The bolster is enough narrower than the 90 transom to afford sufficient space between them to receive the bolster-supporting metallic links *b''*, made, preferably, of toughest and strongest wrought-iron, the said links preferably being bent, as shown in the drawings, to form double 95 loops, so that they may not only embrace the rocker-bar *t*, but also extend under the supporting-bar *t'*, upon which are mounted to rock

the spring-seats t^2 , the supporting-bars t' having preferably at their longitudinal centers a rib, which enters a concavity in the seats t^2 , the seats rocking upon the said bars to a limited extent under the requirements of the springs b^3 and axle.

The rocker-bars t are herein shown as provided at their under sides in the direction of their length with a rounded projection to enter a recess in the top of the saddle c , thus forming a sort of scale-beam bearing, so that the rocker-bar t is free to rock upon the saddle, the rib on one entering a projection on the other and preventing lateral displacement of the rocker-bar, the shoulders t^3 of the saddle preventing longitudinal displacement, or undue longitudinal movement of the rocker-bars upon the saddles. The spring-seats t^2 at opposite sides of the truck are connected, as herein shown, by means of a rod, t^4 , so that the said spring-seats always maintain the same relative distance apart and swing in unison with the bolster b' as the latter moves longitudinally, as it is permitted to do by reason of the links t^5 , resting upon the rocker-bars t , and sustain the supporting-bars t' , upon which the spring-seats are mounted.

In another application filed concurrently herewith, Serial No. 209,962, we have shown spring-seats supported upon like links b^5 ; but the said spring-seats were provided with projections to co-operate with a plate or block attached to the transom, so that the said spring-seats and bolster were not free to rock, or the bolster to move longitudinally crosswise of the car, the links swinging upon the saddle about the arch-bars.

The saddle c is grooved at its lower side to rest upon or embrace the arch-bar c' , the latter being extended longitudinally with relation to the truck and lying at right angles to the bolster b' .

The clips d^6 , at their under sides, have suitable shoulders to embrace the housings, the said clips, at their upper sides, having shoulders, as at 6, against which abut the ends of the arch-bars c' , a lug or upright, 7, of each clip, preferably rounded, being embraced by and serving to hold the truss e , the latter being kept down in engagement with the said lugs by means of a cap, e' , held in position by a bolt, e^2 , which is extended down through the clip and the outer side of the housing, and also through the usual wheel-strap, e^3 , where the said bolt has applied to it suitable nuts. The upper arch-bar, c' , is further attached to the housing by other bolts, as e^4 .

The trusses are composed of round or square metal rods of great strength properly welded or united together to form, preferably, an endless band, the looped ends of which embrace the said lugs or projections 7, the truss extending from the said lugs along the clips d^6 , thence diagonally down over the rounded inner ends 65 of the said clips, as shown in Fig. 2, and under the transom b , affording strong support for the latter.

At each side of the transom b , and in the space formed between it and the truss e and the under side of an arch-bar, c' , we have placed certain arch-bar-sustaining blocks or castings, f , (herein shown as substantially triangular in shape,) the said blocks preventing inward bending, buckling, or crushing of the arch-bars, the upper and lower edges of the said blocks being preferably grooved to receive the arch-bar and the truss e , such construction preventing lateral bending or straining of either the arch-bars or truss. These blocks f have extending inwardly from them right-angled flanges f^2 , which are bolted in place between the arch-bar and truss e and to the sides of the transom b by suitable bolts or rivets, 25, extended through holes 26.

Bolting or riveting the flanges of the blocks 85 to the sides of the transom and connecting the blocks to the arch-bar and truss by means of bolts g , as shown in Fig. 2, extended also through the saddle c and the wheel-straps, form a very rigid truck—one that will keep 90 square under all ordinary uses.

The bolster b' , as herein shown, has at its upper side usual curve-irons, i^2 , and a hub, m , to receive the usual casting at the under side of the usual rocker-bar. (Not shown.)

We may use any usual or suitable brake mechanism in connection with our improved truck.

It will be noticed that the link b^5 is what is called a "double link," or, in other words, it is so made as to straddle the rocking bar t and extend transversely under and so as to sustain the supporting-bar t' and the weight carried on it, including the spring-seat and the bolster; but the employment of two open links 100 to straddle the rocking bar t and embrace the ends of the supporting-bar t' would, we consider, come within the scope of our invention.

From the foregoing description and the drawings to which it refers it will be seen that 110 the weight of the car-body sustained by the supporting-bolster is not applied directly to the transom through the springs b^3 , but is applied through the springs upon the spring-seats, the supporting-bars, the links b^5 , and 115 the rocking bar and saddle, the entire weight of the car being supported, it will be noticed, directly in the line of the arch-bar and truss, which, in what is called a "swing-truck," or in a truck wherein the bolster is free to move 120 longitudinally as well as to rise and fall, is a matter of very great importance, for by locating the spring-seats and springs directly in line with the arch-bar and truss all torsional strains which tend to twist the arch-bar or 125 truss out of shape are obviated or neutralized, as are also strains which tend to shear off the bolts g and e^3 next the arch-bar.

The metallic transom extended across the truck from one to the other side, when employed in a so-called "swing-truck," forms an 130 additional element of safety, which thus becomes a matter of great importance, for with the links b^5 , should they for any cause be

broken the transom will catch and support the supporting-bar t' and the spring-rest and springs, thus preventing any serious accident, for in an emergency the car could be run a 5 trip even though the links b^5 were broken, but it would not, of course, have the same amount of spring and would not ride as easily.

Making the bolster b' of metal, as shown and described, and extending it from side to 10 side of the truck, instead of usual wooden bolsters, enables us to secure ample room within the space between the arch-bar and wheel-straps to sustain the springs which are to support the transom.

15 In this our invention, wherein the bolster is so supported that it is free to swing longitudinally with relation to the truck, it will be noticed that the springs occupy substantially the same position that they do in what is called 20 the "rigid truck," and the weight of the car-body is suspended directly under the arch-bar, the springs occupying such position better resisting the tilting of the car-body than in any other position.

25 The employment of a truss, e , made as an endless loop to embrace the lug 7 of the clip, held in place upon the housing by projections embracing the said housing, is a material element of safety, for in case of breaking the bolts 30 g , which is not unfrequent, strain is not exerted on the housing-bolts so as to shear them off, and the strain on the truss is exerted upon the lug 7, and this strain is counteracted by the end of the arch-bar abutting against the 35 shoulder 6 of the lug 7, and at the same time it will be noticed that the arch-bar-supporting blocks prevent any breaking of the arch-bars.

We claim—

1. In a car-truck, a U-shaped transom, 40 arch-bars, saddle, and rocking bar mounted thereon, combined with links, supporting-bars

mounted thereon, and springs, and a metal bolster supported by the said springs, the bolster entering the said transom, substantially as described.

2. In a car-truck, a metallic transom, the arch-bar, the truss e , housings, clips mounted thereon, and arch-bar-sustaining blocks inserted between the said arch-bar and the truss and transom, and the rocking bar t , combined with the metallic bolster, springs to support it, supporting-bar t' , and loops embracing the said rocking bar, the supporting-bar t' sustaining above it the springs, the latter being located directly below the arch-bar and between it and the truss, substantially as described. 45

3. In a car-truck, a metallic transom, the arch-bar, the truss e , housings, clips mounted thereon, and arch-bar-sustaining blocks inserted between the said arch-bar and the truss and transom, and the rocking bar t , combined with the metallic bolster, springs to support it, supporting-bar t' , and loops embracing the said rocking bar, the supporting-bar t' sustaining above it the springs, the latter being located directly below the arch-bar and between it and the truss, substantially as described. 55
